UNITED STATES PATENT OFFICE.

CHARLES F. MOTZ, OF MONACA, PENNSYLVANIA.

SAND-BLAST MACHINE.

1,351,581.

Specification of Letters Patent. Patented Aug. 31, 1920.

Application filed November 21, 1919. Serial No. 339,674.

To all whom it may concern:

Be it known that I, CHARLES F. MOTZ, a citizen of the United States, and resident of Monaca, in the county of Beaver and State 5 of Pennsylvania, have invented a new and useful Improvement in Sand-Blast Machines; and I do hereby declare the following to be a full, clear, and exact description thereof.

10 My invention relates to sand blasting apparatus.

The object of my invention is to provide an apparatus of this character in which the 15 operation of blasting is done rapidly and efficiently, the action of the apparatus being entirely automatic, the only manual labor being the placing of the ware in position and withdrawing it after it is finished.

To these ends my invention comprises the 20 novel features hereinafter set forth and claimed.

In the accompanying drawings, Figure 1 is a plan view of a portion of my improved apparatus; Fig. 2 is an enlarged elevational 25 view of one of the blasting compartments showing the parts in position for blasting; Fig. 3 is a section on the line 3—3 of Fig. 2; Fig. 4 is a view similar to Fig. 2 showing the door and pattern carrier elevated; and Fig. 30 5 is an enlarged detail of the ware-carrier and pattern-carrier in position thereon.

In the drawings the numeral 2 indicates a 35 rotary frame or table which is mounted on and driven by the central vertical shaft 3. Around the periphery of the frame 2 are the compartments 4 in which the sand blasting operations take place. Each compartment 4 has the opening 5 for the insertion and withdrawal of the ware to be sand-blasted, and 40 said opening is provided with the vertically sliding door 6 which is adapted to move in the guides 7. Connected to the door 6 is the cable 8 which passes up over the pulley 9 mounted on the rocker-shaft 10 journaled in the bearings 11. To the free end of the cable 45 8 is secured the counterweight 12 which is suspended in the space 13 between the different compartments.

A vertical spindle 14 journaled in bearings 50 15 and 16 extends up within the compartment 4 and said spindle carries at its upper end the head 17 which supports the rubber or like flexible ware-support 18. At the lower end of the spindle 14 is the pulley 19

which is driven by the belt 20 connected up 55 to any suitable driving pulley.

The ware-support 18 has the shoulder 21 which forms a seat for the shade 22 or other piece of glassware to be sand-blasted.

The pattern-carrier 23 is composed of the 60 upper and lower plates 24 and 25 connected by the bolts 26. The lower plate 25 has the opening 27 and contained within said opening is the pattern ring 28 which may have any suitable design cut therein. 65

In order to hold the shade 22 securely in position on the support 18 the pattern-carrier is provided with the holder 29 which is adapted to engage the opening 30 in the upper end of the shade 22. A bolt 31 is connected to the holder 29, said bolt passing up through the top-plate 24 of the pattern carrier, and a spring 32 surrounds said bolt and is interposed between the holder 29 and the inner face of the plate 24. The pressure of 70 the spring 32 on the holder 29 when engaging the upper end of the shade 22 acts to hold said shade securely in position on the ware-support 18. 75

A collar 33 is secured to the plate 24 of the 80 pattern-carrier. Screwed into the collar 33 is the swivel-block 34 in which the rod 35 is swiveled. This rod 35 passes up through a guide 36 on top of the compartment. A cable or cord 37 is connected to the upper end of 85 the rod 35 and the said rope passes up over the pulley 38 on the standard 39. The rope 37 then passes over the pulley 40 on the shaft 10 down into the space 13 where the weight 41 is connected to the free end of said rope 37. 90

At the outer end of the shaft 10 is secured the crank-arm 42. A cable 43 is connected to the outer end of said crank-arm, and a weight 44 is connected to the lower end of 95 said rope 43. A stop pin 45 is provided with which the cable 43 engages when the crank-arm 42 is thrown over into position indicated in Fig. 2 where the door is lowered.

Within the compartment 4 is a pocket 46 for the sand or other abrading material, and 100 extending down into said pocket is the pipe 47 which is connected up with the nozzle 48. An air-pipe 49 is connected up with the nozzle, said air-pipe passing outside of the compartment 4 and connected by flexible 105 pipe 50 with the pipe 51 which is supplied with air from the main air-line 52. A valve 53 controls the supply of air from the pipe

52 to pipe 51 and said valve has the bell-crank 54 connected thereto, the valve being automatically operated by one of the arms of said bell-crank engaging the projection 55 in the path of said bell crank to open the valve.

10 A deflector rod 56 is in the path of the movement of the crank-arm 42 and said deflector operates said crank-arm to rock the shaft 10 to raise the door and at the same time lift the pattern-carrier 23, as more fully hereinafter set forth.

15 In the operation of my improved apparatus, the frame 2 is rotated and the operator at the point where the door is lifted by the crank-arm 42 engaging the deflector rod 56 inserts a shade or other piece of ware through the opening 5 and places it on the ware-support 18. Immediately thereafter 20 the crank-arm 42 disengages from the deflector bar 56 and the door of its own weight is lowered, and at the same time the pattern-carrier 23 is likewise lowered bringing the pattern 28 down around the skirt of the shade to be blasted. At the same time the holder 29 engages the opening at the upper end of the shade so as to support the shade securely in position during the blasting operation. As soon as the door is closed in 25 this manner and the pattern-carrier has been lowered, one arm of the bell-crank 54 engages the projection 55 and the valve 53 is opened permitting air to pass into the pipe 49. This blast of air creates a suction in the pipe 47 and the sand is drawn up from the pocket 46 and driven against the shade. As the shade is rotating the blasting action takes place uniformly all over that part of the shade which is exposed, the pattern-ring 28 protecting certain portions of the skirt of the shade which is not acted on by the sand and leaving the design of the pattern on the shade. The blasting continues 30 during the rotation of the table 2 and until 40 the compartment comes around into position where the crank-arm 42 again engages the deflector bar 56, whereupon the door is raised together with the pattern-carrier, as indicated in Fig. 3, which permits the operator 45 to insert a hand to remove the shade which has been sand-blasted and introduce another shade before the crank arm 42 disengages the deflector bar 56 to allow the door to lower.

50 In this manner the operator at one point in the rotation of the table 2 removes a shade and inserts a new one as each compartment comes around to this point, the movement of the parts being so timed that the operator just has time to remove the finished shade and insert another, so that the operator is kept busy withdrawing and inserting the shades, all the other operations, such as the raising and closing of the door, 55 and the raising and lowering of the pattern-

carrier being automatic, as well as the applying and cutting off of air for operating the sand blast.

What I claim is:

1. Sand blasting apparatus comprising a compartment having an opening for the insertion of the ware to be sand-blasted, a rotary ware-support in said compartment, means for rotating said ware support, sand-blasting means, a vertically movable pattern-carrier, a door for said opening and means for raising and lowering said door and simultaneously therewith raising and lowering said pattern-carrier. 70

2. Sand blasting apparatus comprising a compartment having an opening for the insertion of the ware to be sand-blasted, a rotary ware-support in said compartment, means for rotating said ware support, sand-blasting means, a vertically movable pattern-carrier, a door for said opening, means for raising and lowering said door, and means operated by said first-named means for raising and lowering said pattern-carrier. 80

3. Sand blasting apparatus comprising a compartment having an opening for the insertion of the ware to be sand-blasted, a rotary ware-support in said compartment, means for rotating said ware support, sand-blasting means, a vertically movable pattern-carrier, a holder carried by said pattern carrier, a door for said opening, means for raising and lowering said door and simultaneously raising and lowering said pattern-carrier and said holder. 90

4. Sand blasting apparatus comprising a compartment having an opening for the insertion of the ware to be sand-blasted, a rotary ware-support in said compartment, means for rotating said ware support, sand-blasting means, a vertically movable pattern-carrier, a rope connected to said pattern-carrier, a sheave engaged by said rope, a rock-shaft, sheaves on said rock-shaft, a door for said opening, a cable connected to said door passing over one of said sheaves, weights connected to said cables, an arm on said rock shaft, and a cam in the path of said arm. 105

5. Sand blasting apparatus comprising a rotary frame having a series of compartments arranged thereon, each compartment having an opening, a sliding door for said opening, a rotary ware-support in said compartment, means for rotating said ware-support, sand blasting means, and means for automatically raising and lowering said door. 115

6. Sand blasting apparatus comprising a rotary frame having a series of compartments arranged thereon, each compartment having an opening, a sliding door for said opening, a rotary ware-support in said compartment, means for rotating said ware-sup- 120

130

port, sand blasting means, a vertically movable holder, means for raising and lowering said door, and means for bringing said holder in position to engage the ware when said door is lowered.

7. Sand blasting apparatus comprising a rotary frame having a series of compartments arranged thereon, each compartment having an opening, a slidable door for said opening, a rotary ware-support in said compartment, means for rotating said ware-sup-

port, sand blasting means, a vertically movable spring-actuated holder, means for raising and lowering said door, and means for bringing said spring-actuated holder in position to engage the ware when said door is lowered.

In testimony whereof I, the said CHARLES F. MOTZ, have hereunto set my hand.

CHARLES F. MOTZ.

Witness:

JOHN F. WILL.
